(57) CLAIM

The ornamental design for a foot-shaped, mesh scrubber, as shown and described.

DESCRIPTION

FIG. 1 is a top view of a foot-shaped, mesh scrubber;

FIG. 2 is a front view of the foot-shaped, mesh scrubber;

FIG. 3 is a back view of the foot-shaped, mesh scrubber;

FIG. 4 is a bottom view of the foot-shaped, mesh scrubber;

FIG. 5 is a left side view of the foot-shaped, mesh scrubber;

FIG. 6 is a right side view of the foot-shaped, mesh scrubber; and,

FIG. 7 is a top view of a foot-shaped, mesh scrubber with a cord.

The dashed lines in the figures are not part of the patented design.
